UNITED STATES PATENT OFFICE.

IRA M. CLARKE, OF NEW MARTINSVILLE, WEST VIRGINIA.

DESIGN FOR A GLASS JAR OR SIMILAR CONTAINER.

Application filed January 7, 1926. Serial No. 15,992. Term of patent 3½ years.

To all whom it may concern:

Be it known that I, IRA M. CLARKE, a citizen of the United States, residing at New Martinsville, in the county of Wetzel, State of West Virginia, have invented a new, original, and ornamental Design for a Glass Jar or Similar Container, of which the following is a specification, reference being had to the accompanying drawing, forming part thereof.

Figure 1 is a perspective view of the article with the top in position.

Figure 2 is a side elevation of Figure 1.

I claim:

The ornamental design for a glass jar or similar container, substantially as shown.

IRA M. CLARKE.
